(57) CLAIM

The ornamental design for a pub table, as shown and described.

DESCRIPTION

FIG. 1 is a front corner perspective view of a pub table according to an embodiment of the invention. The view from the opposite back corner being identical to this view.

FIG. 2 is a side elevational view of a pub table according to an embodiment of the invention. The view from each side being identical hereto; and,

FIG. 3 is a top plan view of a pub table according to an embodiment of the invention.

The portions of the figures shown in dashed lines are for illustrative purposes only and form no part of the claimed invention.

1 Claim, 3 Drawing Sheets
